UNITED STATES PATENT OFFICE.

FRANK H. BECK, OF LARCHMONT, NEW YORK.

DESIGN FOR A PENCIL DISPLAY HOLDER.

Application filed September 21, 1921. Serial No. 502,308. Term of patent 7 years.

To all whom it may concern:

Be it known that I, FRANK H. BECK, a citizen of the United States, and a resident of Larchmont, county of Westchester, and State of New York, have invented a new, original, and ornamental Design for Pencil Display Holder, of which the following is a specification, reference being had to the accompanying drawing, forming part hereof.

I claim:

The ornamental design for a pencil display holder, as shown.

FRANK H. BECK.
